UNITED STATES PATENT OFFICE.

DELMER W. CALL, OF CLEVELAND, OHIO, ASSIGNOR TO THE NATIONAL
MALLEABLE CASTINGS COMPANY, OF SAME PLACE.

HUB-BAND.

SPECIFICATION forming part of Letters Patent No. 681,667, dated August 27, 1901.

Application filed April 13, 1901. Serial No. 55,876. (No model.)

To all whom it may concern:

Be it known that I, DELMER W. CALL, of Cleveland, in the county of Cuyahoga and State of Ohio, have invented a new and useful Hub-Band, of which the following is a full, clear, and exact description, reference being had to the accompanying drawings, forming part of this specification, in which—

Figure 1 is an elevation, partly in section, showing the cap in place. Fig. 2 is a cross-section on the line II II of Fig. 1 looking outwardly, showing the cap in place. Fig. 3 is cross-section on the line III III of Fig. 1, the cap being removed. Fig. 4 is a section of the end portion of the hub-band, the cap being removed. Fig. 5 is an elevation of the cap; and Fig. 6 is an elevation, partly in section, of the collar.

My invention is designed to provide a hub-band of greater strength and durability than has heretofore been known.

In the drawings, 2 represents a hub-band which is formed on its interior surface near its end with a rib or ridge 3, which may be a complete circle or may be interrupted, as desired.

4 is a sheet-metal collar, which is fitted upon the end of the hub-band, having an inner annular flange B and an outer annular flange C, which fit, respectively, the inner and outer surfaces of the band. The inner flange is provided with slots 5, which extend slightly above (on the outer side) of the rib, and thus constitute openings for the recep-

tion of the fastening devices on the cap described below. The collar is held in place by forcing the metal of the inner flange inwardly behind the rib. Preferably the parts of the flange thus forced in are directly adjacent to the slots; but, if desired, the metal may be forced in around the entire circumference of the flange. By combining the slotted flange with the interior rib I secure important results, because the rib serves to hold and strengthen the flange of the collar 4, and as the slots are in front of the rib the collar is held out sufficiently to provide sockets for the holding devices without weakening the flange or rendering it liable to be torn. The cap, which is fitted to the end of the hub-band, has an inwardly-projecting flange 6, which fits within the collar and has spring-actuated catches 7, which are preferably inclined laterally and are adapted to take into the slots above mentioned.

I claim—

A hub-band having at its end a collar with inner and outer flanges, a rib on the interior of the hub-band, and slots in the inner flange of the collar which extend to the outer side of the rib; substantially as described.

In testimony whereof I have hereunto set my hand.

DELMER W. CALL.
